Patented Mar. 13, 1917.

UNITED STATES PATENT OFFICE.

WILLIAM F. DESSO, OF SOMERS, CONNECTICUT.

CAN-Straightening Machine.

1,218,633.

Specification of Letters Patent. Patented Mar. 13, 1917.

Application filed July 29, 1916. Serial No. 112,123.

To all whom it may concern:

Be it known that I, WILLIAM F. DESSO, a citizen of the United States, residing at Somers, in the county of Tolland and State 5 of Connecticut, have invented or discovered certain new and useful Improvements in Can-Straightening Machines, of which the following is a specification, reference being had therein to the accompanying drawing.

10 This invention relates to can straightening machines and has for its object to provide a convenient and efficient machine for straightening or removing dents from milk cans and the like. To this end the invention 15 comprises a straightening block having a pivoted connection with an operating lever so that the said straightening block may be carried far enough from said lever to adapt it to operate on cans of relatively large 20 diameter, and still be adapted, by being brought into line with said lever, or approximately so, to be inserted into the relatively small mouths of such cans. The straightening block coöperates with a bed-plate prefer- 25 erably loosely supported on a table, and the can to be straightened will be placed on said bed-plate and the straightening block, which will operate from the inside of the can, will be pressed, by its operating lever, 30 into forcible contact with the inside of the can located on said bed-plate. As the bed-plate is loosely supported on the table referred to it may be moved into different positions, to accommodate different sizes of 35 cans; or, if desired, interchangeable bed-plates of different shapes and sizes may be provided for coöperation with the straightening block.

In the accompanying drawing Figure 1 is 40 a side view of a can straightening machine embodying the present invention, and Figs. 2 and 3 are opposite end views thereof. Fig. 4 is a detail perspective view of the work- 45 supporting bed-plate.

Referring to the drawings, 12 and 13 de- 50 note U-shaped standards adapted to be se- cured to a floor or platform, and on the tops of which is mounted a support or table 14 preferably consisting of an angle-iron or 55 steel bar having upwardly projecting side flanges. The rear standard 13 affords bear- ings for a driving shaft 15 having a pulley 16 to be belted to any suitable source of power, and having a second pulley 16^a con- 60 nected by a belt 17 with a pulley 18 on a cam

shaft 19 journaled in bearings afforded by standards 20 secured to the table 14.

The shaft 19 is provided with a scroll- 65 cam 21 which is engaged by the weighted rear end of a lever 22 fulcrumed in a support 60 or standard 23 fixed to and extending up- 70 ward from the table 14. Preferably con- 75 nected by a link 24 with the forward end of the lever 22 is a pressing straightening block 25. The hinged or pivoted loose connection 80 (which is preferred) of the block 25 with the said link 24, enables the said block to adjust itself more or less to the work, while the pivoted connection of the link 24 with the lever 22 permits the said link and block 85 70 to be swung to a horizontal position, as de- 75 noted by dotted lines in Fig. 1, in being en- 80 tered into the mouth of a can which may be too small to receive these parts when they are in a vertical or working position as 85 shown in full lines in Fig. 1. Thus the straightening block 25 may be far enough 90 from the lever 22 so that it may operate on a can of relatively large diameter, and may still be readily entered into a relatively small 95 mouth of such can. Interchangeable straightening blocks 25, of different shapes or sizes, for different kinds of work, may be provided, if desired, and the said block might be rigid with an arm pivoted to the 100 lever 22 and still be adapted to be swung up so as to be in line with said lever, or ap- 105 proximately so.

Loosely supported on the table 14 is a bed 90 plate 26 which will preferably have a con- 95 cave upper surface or seat to receive the cans to be straightened, said bed-plate hav- 100 ing an opening 27 of suitable size and shape to receive a handle of a can, when necessary. The straightening block 25 is preferably 95 formed with a transversely convex lower face so that it will properly coöperate with the concave upper face of the bed-plate 26, and between which bed-plate and said block the can body to be straightened will be dis- 105 posed in the straightening operation.

The belt 17 connecting the flanged pulleys 16^a and 18 is normally slack, so that the shaft 19 will normally be stationary; but when a can to be straightened is placed in straight- 105 ening position the attendant depresses the forward end of a treadle lever 28 thus forc- 110 ing a belt-tightening pulley 29, at the rear end of said lever, against the belt 17 and thereby setting the shaft 19 in motion so as 110

to cause the scroll cam 21 on said shaft to depress the forward end of the lever 22 to bring the straightening block 25 into forcible contact with the inside of a can supported on the bed plate 26. Said bed-plate 26 is free to be moved lengthwise on the table 14 to bring different parts of a can lying thereon into register with the straightening block 25, and the can may be turned 10 to different positions on said bed-plate for the same purpose. When the high part of the scroll cam passes the lever 22, the weighted rear end of which rests on said cam, the straightening block 25 at the forward end of 15 said lever will be lifted by the overbalancing or weighted rear end of said lever. When the treadle lever 28 is released its forward end will be lifted by a spring 30 to slacken the belt 17 and thus disconnect the shaft 19 20 from the driving shaft 15, the upward movement of said treadle lever, under the action of said spring, being arrested by a stop-pin 31 on the standard 12.

The operation of the machine will be 25 readily understood from the foregoing, and it will also be understood that the invention is not necessarily limited to the details herein shown and described, and that any well-known equivalent device, as a clutch connection, may be substituted for the belt 30 tightener herein shown and described, for connecting the cam-carrying driven shaft with a driving shaft or source of power.

Having thus described my invention I 35 claim and desire to secure by Letters Patent:

1. In a can straightening machine, the combination with a bed-plate and means for supporting same, of a straightening block coöperating with said bed-plate, a lever with 40 which said straightening block has a hinged or pivoted connection so that it may be readily entered into the relatively small mouth of a can by being swung upward into line with said lever, and means for operating 45 said lever to force said straightening block toward said bed-plate.
2. In a can straightening machine, the combination with a bed-plate and means for supporting same, of a straightening block 50 coöperating with said bed-plate, a lever with which said straightening block has a hinged or pivoted connection so that it may be readily entered into the relatively small mouth of a can by being swung upward into 55 line with said lever, and means for operating said lever to force said straightening block toward said bed-plate, said operating means consisting of a scroll cam acting on the end of said operating lever opposite that 60 at which the said straightening block is lo-

cated, and a rotating shaft by which said cam is carried.

3. In a can straightening machine, the combination with a bed-plate and means for supporting same, of a straightening block 65 coöperating with said bed-plate, a lever with which said straightening block has a hinged or pivoted connection so that it may be readily entered into the relatively small mouth of a can by being swung upward into 70 line with said lever, means for operating said lever to force said straightening block toward said bed-plate, said operating means consisting of a scroll cam acting on the end of said operating lever opposite that at 75 which the said straightening block is located, a rotating shaft by which said cam is carried, and means for connecting and disconnecting said shaft with a driving shaft or other source of power.

4. In a can straightening means, the combination with a work support or table, of standards on which the said work-support or table is mounted, a work-sustaining bed-plate loosely mounted on said work support 85 or table, so as to be movable thereon and thus be manually adjustable, with the article resting thereon, to different positions, a straightening block coöperating with said bed-plate, a lever at the forward end of 90 which said straightening block is carried, a cam for operating said lever and which is engaged by the rear end of said lever, a shaft on which said cam is mounted, and means for connecting and disconnecting said shaft 95 with a driving shaft or other source of power.

5. In a can straightening means, the combination with a work support or table, of standards on which the said work-support 100 or table is mounted, a work-sustaining bed-plate loosely mounted on said work support or table, so as to be movable thereon and thus be manually adjustable, with the article resting thereon, to different positions, a 105 straightening block coöperating with said bed-plate, a lever by which said straightening block is carried and which has a weighted rear end normally resting on said cam, a cam for operating said lever, a shaft on 110 which said cam is mounted and which is provided with a pulley, a driving shaft also provided with a pulley, a belt connecting said pulleys, and a treadle-operated belt-tightening device which may be forced into 115 contact with said belt when the cam shaft is to be set in operation.

In testimony whereof I affix my signature,

WILLIAM F. DESSO.
